UNITED STATES PATENT OFFICE.

CHARLES A. COLLEN, OF KALAMAZOO, MICHIGAN, ASSIGNOR OF ONE-HALF
TO CLAUDE DECKER, OF KALAMAZOO, MICHIGAN.

JOINT-BREAKING DEVICE FOR CARRIAGE-TOPS.

SPECIFICATION forming part of Letters Patent No. 739,391, dated September 22, 1903.

Application filed February 17, 1902. Serial No. 94,430. (No model.)

To all whom it may concern:

Be it known that I, CHARLES A. COLLEN, a citizen of the United States, residing at the city of Kalamazoo, in the county of Kalamazoo and State of Michigan, have invented a certain new and useful Improvement in Brace-Joint-Breaking Devices for Carriage-Tops, of which the following is a specification.

This invention relates to improvements in brace-joint-breaking devices for carriage-tops.

Much difficulty is experienced when the storm or side curtains of a top are in position on the same in breaking the joint of the braces of the top, so that the same may be collapsed or lowered, it often being quite impossible to do so unless the operator is out of the carriage.

The object of this invention is to provide an improved device for breaking joints in the braces of carriage-tops which may be operated by a person in the carriage and accomplish the objects in an effective manner and still be simple and inconspicuous.

A further object is to provide a device for the purpose which may be attached to practically any carriage-top without special adaptation for the particular structure on which it is to be used.

Further objects will definitely appear in the detailed description to follow.

I accomplish the objects of my invention by the devices and means described in the following specification and clearly pointed out in the claims.

A structure embodying the features of my invention is fully illustrated in the accompanying drawings, forming a part of this specification, in which—

Figure 1 is a side elevation view of a carriage-top with a structure embodying the features of my invention in position on the same. Fig. 2 is a detail sectional view taken on a line corresponding to line 2-2 of Fig. 1. Fig. 3 is a detail sectional view taken on a line 3-3 of Fig. 2. Fig. 4 is a side elevation view of the butt-end of the operating-lever F.

In the drawings, the sectional views are taken looking in the direction of the little arrows at the ends of the sectional lines, and similar letters of reference refer to similar parts throughout the drawings.

Referring to the lettered parts of the drawings, A represents a clip adapted to be se-

cured upon the bow of the carriage-top, as a. To one side of the clip A is a lug or projection 55 A', adapted to receive the bolt or shaft D through the same. The shaft D is preferably threaded into this bearing, as that serves as an effective antirattle construction. On the outer end of the shaft D are levers or arms 60 E E', suitably shaped so that the outer end of the arm E will engage the jointed brace B and the outer end of the arm E' will engage the jointed brace C. On the inner end of the shaft D is a hand-lever F, which is inside of 65 the carriage-top in convenient reach of a person in the carriage. An upward movement of the lever F will break the joint of the brace B and permit the forward portion of the top to be collapsed, and a downward motion 70 of the same lever will break the joint of the brace C and permit the top to be lowered, as may be desired.

I have illustrated and described my improved brace-joint-breaking device for carriage-tops in the form I believe to be the most simple. I am aware, however, that it is capable of considerable structural variation without departing from my invention.

Having thus described my invention, what 80 I claim as new, and desire to secure by Letters Patent, is—

1. In a device of the class described, the combination of a supporting-clip A, adapted to be secured on a bow of a carriage-top; a 85 screw-threaded bearing carried thereby; a screw-threaded shaft D; arms on the outer end thereof adapted to engage the braces of a carriage-top; and a suitable handpiece on the inner end of said shaft, for the purpose 90 specified.

2. In a device of the class described, the combination of a screw-threaded bearing; means for securing the same to a bow of a carriage-top; a screw-threaded shaft supported thereby; an arm on the outer end of the said shaft adapted to engage a brace of the carriage-top; and a suitable handpiece on the inner end of said shaft, for the purpose 95 specified.

In witness whereof I have hereunto set my hand and seal in the presence of two witnesses.

CHARLES A. COLLEN. [L. S.]
